UNITED STATES PATENT OFFICE

ORA S. JACKSON, OF OMAHA, NEBRASKA, ASSIGNOR TO GENERAL STEEL CASTINGS CORPORATION, OF GRANITE CITY, ILLINOIS, A CORPORATION OF DELAWARE

LOCOMOTIVE STRUCTURE

Application filed November 14, 1929. Serial No. 407,198.

My invention relates to railway rolling stock and consists in a novel locomotive frame and air reservoir construction.

The main object of my invention is to construct an air reservoir adapted to be placed longitudinally of the locomotive between and connected to the side frames thereof, such reservoir and its connections to the side frames being adapted to form a substantial reinforcement for the frames and to share the longitudinal forces imposed on said frames. The reservoir may be formed of a plurality of members each of arcuate cross section and flanged to engage the adjacent member or members.

In the accompanying drawings illustrating my invention—

Figure 1 is a side elevation of a reservoir adapted to be applied to separately formed side frames which are indicated in outline.

Figures 2 and 3 are vertical sections taken substantially on the lines 2—2 and 3—3 of Figure 1.

Figures 4 and 5 are similar detail sections illustrating modifications in the parts indicated.

Figure 6 is a top view of one longitudinal half of another form of my invention.

Figure 7 is a side elevation of the same.

Figure 8 is a cross section of the same structure, the left hand side of the figure being taken on the line 8—8 of Figure 7 and the right hand side of the section being taken on the line 8^a—8^a of Figure 7.

Figure 9 is a top view of one longitudinal half of another form of my invention.

Figure 10 is a side elevation of the same.

Figure 11 is a cross section, the left hand side of which is taken on the line 11—11 of Figure 10 and the right hand side of which is taken on the line 11^a—11^a of Figure 10.

Figure 12 is a top view of another modification of my invention.

Figure 13 is a side elevation of the same.

Figure 14 is a cross section, the left hand side of which is taken on the line 14—14 of Figure 13 and the right hand side of which is taken on the line 14^a—14^a of Figure 13.

Figure 15 is a cross section illustrating a further modification.

Figure 16 is a cross section illustrating another modification.

In the construction shown in Figures 1, 2 and 3, the reservoir comprises two main portions 1 and 2 extending longitudinally of the locomotive. The lower or body portion 1 resembles a trough in outline and the upper portion 2 resembles an inverted trough fitting over portion 1. Preferably, each of these portions comprises a casting which can be made of any desired width, length and thickness to provide required strength and capacity.

The lower portion 1 is provided with integral brackets 3 and 4 for attachment to the locomotive side frames 5. Each bracket 4 includes a downward extension 6 which may be bolted or otherwise secured to the pedestal leg 7.

Suitable vertical ribs 8 extend transversely and exteriorly of the reservoir body between brackets 3 and 4, reinforcing the same and the body of the reservoir portion and also extending between and reinforcing horizontal flanges 9 extending around the upper edges of reservoir portion 1 and adapted to be joined with corresponding flanges 10 formed on the lower edges of the upper portion 2 of the reservoir. Other reinforcements 11 are provided at intervals for bracing flanges 9 and 10 at additional points.

The lower reservoir portion 1 is preferably provided with integral expansion plate brackets 12 which extend upwardly beyond the connecting flanges 9 and 10 and the upper reservoir portion is provided with integral brackets 13 for holding radiating pipes 14.

A relatively deep transverse web 15 braces the vertical brackets 6 throughout their depth and serves as a brace for the corresponding pedestals. This web is provided with a horizontal flange 16 at its lower edge and with suitable openings 17 for lightening the section.

The two reservoir portions 1 and 2 may be united by any suitable means, such as bolting, riveting or welding and, when completely assembled with the locomotive frames, constitute a substantial part of the

framing thereby greatly reinforcing the sides and, if desired, making it possible to use side frames of less weight than would be practical with the ordinary framing with the reservoir mounted on the exterior of the boiler shell.

The structure is adapted to transmit forces longitudinally, vertically or transversely and by forming the expansion sheet brackets 12, radiating pipe brackets 13, brake hanger brackets 18 and connecting members 6 integral with the reservoir a large amount of fitting and assembling work is eliminated which is usually required for the application of these and similar parts to the locomotive frame.

In the structure illustrated in Figure 4, the upper portion 19 of the reservoir has the expansion plate brackets 20 integral therewith and extending around the exterior of the reservoir section, as indicated at 21, to form a substantial reinforcement of the body of the reservoir. The brake hanger lugs 22 are integral with the lower reservoir section 23 as in the preferred construction.

In the construction shown in Figure 5, the brake hanger lug 24 and the expansion plate bracket 25 are both formed integrally with the upper section 26 of the reservoir and the lower section 27 terminates with the bracket 28 by which it is secured to the side frames 29.

In the structure illustrated in Figures 6, 7 and 8, the reservoir is split vertically along its center line and the two sections 30 and 31 are secured to each other in any suitable manner, for example, by the provision of riveted flanges, as indicated at 32. Each section includes suitable brackets 33 for attachment to the frame 34 and also includes one or more transverse braces 35 for connection to pedestal jaws 36 of the frame. Similarly, each section includes pipe brackets 37, expansion plate brackets 38, and brake hanger brackets 39.

In Figures 9, 10 and 11, the complete reservoir is embodied in a single structure 40 which is applied as a unit to the side frame 41 by means of the brackets 42, certain of which brackets also include the brake hanger brackets 43 and expansion plate brackets 44. The pipe brackets 45 are integral with the reservoir and the deep cross bar 46 is also integral with the reservoir and is attached to the frame pedestals 47 as in the other structures previously described. If a reservoir of this type is formed by casting, as is my preferred construction, formation of the body will require a cylindrical core and, to facilitate the molding and casting operation, the shell of the reservoir will be provided with a series of openings 48 which are closed upon the completion of the device by welding suitable cover plates 49 to the body of the reservoir.

Figures 12, 13 and 14 illustrate another

modification of my invention in which the lower portion 50 of the reservoir is formed integrally with the side frames 51 of the locomotive, suitable transverse members 52 corresponding generally to the brackets 3 and 4 of the preferred structure but merging with the sides of the locomotive frame. The brake hanger brackets 53 and the expansion plate brackets 54 are integral with the sides of the frame. Preferably, but not necessarily, the sides of the reservoir body 50 are connected at intervals by suitable braces 55. The upper portion 56 of the reservoir is formed separately and applied to the main body portion 50, preferably by welding, as indicated at W, and this upper portion includes pipe brackets 57 corresponding to the pipe brackets in the other forms of my invention.

Variation in this construction is illustrated in Figure 15 in which the sides of the body 58 of the reservoir terminate about level of the center of the reservoir and the upper section 59 is of larger extent than that indicated in Figures 12 to 14. Lateral flanges 60, on the upper section, are bolted to suitable pads 61 provided on the main structure. Preferably, each of the reservoir portions is suitably braced by braces 62 and 63, respectively, brace 62 being of deeper section to adequately brace the frame transversely of its length.

The modification illustrated in Figure 16 includes a main portion 64, the sides of which extend to a higher level than indicated in Figures 14 and 15 and the reservoir body is completed by the addition of a plain arcuate section 65 which may comprise a sheet of boiler plate, if desired. This element 65 overlaps the edge portions of member 64 and is secured thereto by screws 66 and by welding as indicated at W. By providing a suitable man hole in the reservoir, rivets may be substituted for screws 66. In all the forms of my invention, the general objects stated at the beginning of the specification are attained to a substantial degree. The material usually required for separately fabricating and mounting the ordinary reservoir tanks may be used to form a part of and strengthen the locomotive underframe and the space taken up on the exterior of the locomotive boiler by the usual reservoir may be used for other purposes. The center of gravity of the locomotive structure is lowered by carrying the air reservoirs between the sides of the framing instead of at a substantial height above the same.

In connection with the present application, I refer to my copending application Serial No. 407,199, filed of even date, some features of which are common to the present application.

Various modifications in the details and arrangement of the reservoir and associated parts other than those illustrated and de-

scribed in this and my aforesaid copending application may be made without departing from the spirit of my invention and I contemplate the exclusive use of such variations as come within the scope of my claims.

5 I claim:

1. A locomotive framing member having a recess in the top thereof forming a portion of an air reservoir.

10 2. A locomotive framing member in one piece and having a recess forming the lower portion of an air reservoir.

15 3. In a locomotive underframe, spaced side members having pedestal openings therein, a longitudinally extending member connected to and located between said side members and having a recess forming a portion of an air reservoir.

20 4. In a locomotive underframe, a central member adapted to contain air under pressure and comprising a plurality of separately formed parts each extending the full length of said member.

25 5. In a locomotive underframe, a central member adapted to contain air under pressure and comprising upper and lower portions formed separately, and expansion sheet brackets formed integrally with the lower portion of said member and extending above

30 the level of the bottom of said upper portion.

35 6. In a locomotive underframe, a central member adapted to contain air under pressure and comprising upper and lower portions formed separately, and lugs for mounting radiating pipes formed integrally with the upper portion of said member.

40 7. A locomotive framing member having a recess in one face forming a portion of an air reservoir.

45 8. In a locomotive, driving wheels and an air reservoir located between said wheels and comprising a plurality of separately formed sections, the joint between said sections extending longitudinally of the locomotive.

50 9. In a locomotive, driving wheels, and an air reservoir located between said wheels and comprising a plurality of separately formed sections.

55 10. In a locomotive, driving wheels and an air reservoir located between said wheels and comprising a plurality of separately formed sections, and a brake hanger bracket integral with one of said sections.

60 11. In a locomotive underframe, a central member adapted to contain air under pressure and comprising upper and lower sections formed separately, and an expansion sheet bracket integral with one of said sections.

65 12. In a locomotive underframe, a central member adapted to contain air under pressure and comprising upper and lower sections formed separately, and lugs for mounting radiating pipes formed integrally with one of said sections.

13. In a locomotive underframe, a central member adapted to contain air under pressure and comprising a plurality of sections, flanges on the edges of said sections, and means cooperating with said flanges for holding said sections together.

70 14. In a locomotive underframe, a plurality of separately formed elements secured together and cooperating to form an air reservoir extending lengthwise of the frame and adapted to transmit forces applied to the underframe.

75 15. In a locomotive underframe, a plurality of separately formed castings each of concavo-convex shape with outwardly projecting flanges adapted to be secured to the corresponding flanges on the adjacent casting or castings, said castings cooperating to form an air reservoir extending lengthwise of the underframe and forming a substantial force-transmitting part of the underframe.

80 16. In a locomotive underframe, spaced longitudinal elements including pedestal jaws, and a trough-like member extending longitudinally of the under frame between said elements for transmitting forces applied to the underframe.

85 17. In a locomotive underframe, spaced longitudinal elements including pedestal jaws, a trough-like member extending longitudinally of the underframe between said elements for transmitting forces applied to the underframe, and a separate member for covering said trough-like member to form therewith a closed reservoir.

90 100 18. In a locomotive underframe, spaced longitudinal elements including pedestal jaws, a trough-like member extending longitudinally of the underframe between said elements for transmitting forces applied to the underframe, and a separately formed member applied to and covering said trough-like member and cooperating therewith to form a force-transmitting portion of the underframe and also to form an air reservoir.

105 110 19. In a locomotive underframe, spaced longitudinal elements including pedestal jaws, a trough-like member paralleling said elements with its concave side facing upwardly, braces between said elements and member at intervals, and a separately formed concavo-convex cover member with its concave side facing downwardly, there being transversely extending reinforcing elements on the outer side of said cover member.

115 120 20. In a locomotive underframe, an elongated reservoir member of arcuate cross section provided with outwardly projecting flanges along its longitudinal edges for attachment to a cooperating member, and transverse ribs on said member extending between said flanges on opposite sides of said member.

125 130 21. In a locomotive underframe, spaced longitudinal elements including pedestal jaws, a trough-like member paralleling said

elements with its concave side facing upwardly, and braces between said member and said elements having extensions to engage said pedestal jaws.

5 22. In a locomotive underframe, spaced longitudinal elements including pedestal jaws, a trough-like member paralleling said elements with its concave side facing upwardly, vertical braces integral with said
10 member and extending between said member and said elements, and means between said braces and said pedestal jaws, said means being connected by a transverse web integral therewith, said web being provided with a
15 horizontal flange and opening or openings for lightening the section.

23. In a locomotive underframe, spaced side members, each including a series of pedestals and a longitudinally disposed member
20 connected to and located between said side members and having a recess in the top thereof of forming the lower portion of an air reservoir.

24. In a locomotive underframe, spaced longitudinal elements including pedestal jaws, a trough-like member paralleling said elements with its concave side facing upwardly and a brace integral with said member and having integral extensions to engage said pedestal jaws.

25. In a locomotive, an axle, driving wheels on said axle, and an air reservoir comprising a plurality of separately formed sections located between said wheels and extending over
35 said axle.

26. In a locomotive underframe, separately formed side members having pedestal openings therein, a longitudinally extending reservoir located between said members and comprising a plurality of sections, transverse members integral with at least one of said sections and connected to said side members, and brake hanger brackets integral with said reservoir and transverse members.

27. In a locomotive underframe, separately formed side members, a longitudinally extending reservoir located between said members and comprising a plurality of sections, crossties, and brackets integral with at least one of said sections, said crossties being connected to said side members.

28. In a locomotive frame, side members, a centrally located tank comprising a plurality of sections secured to each other, and a plurality of transoms spaced longitudinally of said side members and connecting the same to each other and to at least one of said sections.

In testimony whereof I hereunto affix my signature this 8 day of November, 1929.

ORA S. JACKSON.
